(57) CLAIM

The ornamental design for a bottle, as shown and described.

DESCRIPTION

FIG. 1 is a top perspective view of a bottle according to our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom perspective view thereof.

The broken lines in the figures illustrate portions of the bottle that form no part of the claimed design. The dash-dot-dash lines immediately adjacent to the claimed areas in the views represent the boundaries of the claimed design and form no part thereof. None of the broken lines form any part of the claimed design.
